UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,214,170.

Specification of Letters Patent. Patented Jan. 30, 1917.

Application filed July 16, 1915. Serial No. 40,333.

To all whom it may concern:

Be it known that I, JOHN KIEWICZ, a citizen of the United States, residing at Boston, county of Suffolk, State of Massachusetts, have invented an Improvement in Sewing-
5 Machines, of which the following description, in connection with the accompanying drawing, is a specification, like characters on the drawing representing like parts.

10 This invention relates to sewing machines of that class which are provided with thread-cutting and clamping devices that operate to hold the end of the needle thread while the initial stitches are being formed and then to cut said end close to the goods. In
15 sewing machines which are provided with this thread-clamping and cutting mechanism, the end of the thread which is cut after the first few stitches have been formed is apt to become entangled in the stitches as they are made and sewed to the goods, thus producing an imperfect product and necessitating the subsequent removal by hand of these severed ends from the stitches.

20 It is the object of my invention to provide a novel mechanism for automatically removing the severed ends as soon as they are severed, thus obviating the possibility of said ends becoming sewed into the goods.
25 The means I have herein illustrated for this purpose is pneumatic means adapted to deliver a blast of air in a direction to blow the severed ends out of the way as soon as they are severed.

30 While my invention is applicable to any sewing machine having a thread-cutting and clamping means such as above described by which a severed end of thread is produced, I have chosen herein to illustrate it
35 as it would be used in a sewing machine having the thread-cutting and clamping devices that are illustrated and described in my co-pending application Se. No. 878,848, filed December 24, 1914.

40 In the drawings, Figure 1 is a side view of a portion of a sewing machine of the type shown in said above-mentioned application and having my improvements applied thereto. Fig. 2 is a plan view of the thread-
45 cutting and clamping device showing the end of the thread clamped; Fig. 3 is a fragmentary plan view of the same elements showing the clamped end of the thread severed and in position to be removed by my
55 improved device.

I have shown at 1 the frame of a sewing machine carrying stitch-forming mechanism which includes a needle 2 carried by a reciprocating needle bar 3 of usual construction.

60 4 indicates a driving shaft from which the stitch-forming mechanism is operated by any suitable or usual connections.

5 and 6 designate two clamping members between which the work to be stitched is retained, the lower clamping member 5 being carried by suitable clamp plates 7 and the upper clamping member 6 being carried by pivotally-mounted arms 8. The clamping members 5 and 6 and the stitch-forming mechanism are constructed to have a relative movement to provide for the necessary feeding movement of the work as the stitching proceeds and in the particular machine herein shown, which is a buttonhole 75 sewing machine of the so-called "Reece" type, this feeding movement is derived from the main cam 9, shown in dotted lines in Fig. 1, by mechanism which it is not necessary to herein describe in detail as it forms 80 no part of the present invention. Said main cam is journaled in the machine and is shown as operated from the driving shaft 4, this being herein accomplished by providing a worm wheel 10 that meshes with 85 teeth formed on the periphery of the cam 9, and which in turn is actuated by a pawl carried in the oscillating pawl carrier 11 and co-operating with the ratchet 12 fast with the gear 10. The pawl-carrier 11 is 90 connected by a link 13 with an elbow-lever 14 pivoted to the frame at 15 and actuated by a cam or eccentric 16 on the shaft 4. Inasmuch as the parts thus far described are 95 those found in the well-known "Reece" buttonhole sewing machine, it is not necessary to further illustrate them herein.

The machine herein shown is also provided with a thread-cutting and clamping device similar to that shown in my co-pending application Se. No. 878,848, above referred to, and which comprises a relatively-fixed thread-clamping plate 20 carried by an arm 21 secured to one of the arms 8 of the work-clamping device, and a relatively-movable hook-shaped thread-holding member 22 carried by a lever 23 that is pivoted at 24 to the arm 8. The device also comprises a thread-cutter 25 actuated by a lever 26 pivoted at 27 to the arm 8. Said levers 110

23 and 26 are actuated at the proper time by arms 27 and 28 carried by rock shafts 29 journaled in the frame and actuated from the cam 9 at suitable times. For a further 6 and more full description of these parts, reference may be had to the above-mentioned application, it being sufficient herein to state that as the sewing machine is brought to rest after a stitching operation with the needle raised, the thread-holder 22 is given a 10 movement into the dotted line position Fig. 2 to cause the hooked end thereof to engage the needle thread *t* between the raised needle and the work and is then moved laterally into the full line position Fig. 2, to 15 clamp the thread between itself and the plate 20. At this time the thread cutter 25 is actuated to cut the thread between the thread clamp and the work, thus leaving 20 the end of the thread *t* leading from the needle clamped between the members 22 and 20. When the stitching operation is commenced again, the end of the needle thread 25 will remain clamped between the parts 22 and 20 until after the initial stitches have 30 been formed and the needle thread has been firmly anchored in the goods, at which time the cutter 25 is given a thread-cutting movement thereby severing the end *t'* of the thread close to the work and at the same 40 time the thread holder 22 is moved backwardly into the position shown in Fig. 3, thereby releasing the severed end *t'*. The mechanism as thus far described is or may be 45 all as shown in my said co-pending application.

When the end *t'* of the needle thread is severed, as shown in Fig. 3, it drops onto the work and is very apt to be caught into 50 the stitching being made and thus stitched to the work. This is undesirable as it results in an imperfect product and necessitates the removal by hand of these several ends after the stitching operation is completed.

I have provided herein a novel mechanism for automatically removing these thread ends *t'* and which comprises a blower or 55 pneumatic device constructed to deliver blasts of air in a direction to blow the ends *t'* away as soon as they are severed and released by the thread-holding means. While any suitable blower mechanism might be employed for this purpose I have herein 60 illustrated a device comprising a bellows which is actuated from some moving part of the machine and which has a delivery pipe connected thereto that terminates adjacent the thread-cutting and clamping device. This bellows is shown at 34 and is herein illustrated as located within a chamber 35 formed in the frame 1 of the machine. The bellows is shown as secured to a removable cap 36 by which the upper end 65 of the chamber 35 is closed, and said cap

has a port 37 therein communicating with the bellows which also communicates with an air delivery pipe 38, the end 39 of which is situated directly above the thread-clamping and cutting device. This pipe 38 is shown as secured to the frame 1 by means of a clamping device 40. The bellows 35 may be operated in any suitable way. I have herein shown a construction whereby it is operated from the rocking arm or lever 14 forming part of the means for actuating the main cam 9, and for this purpose the bellows has depending therefrom a stem 41 which extends through the bottom of the chamber 35 and is connected by a link 42 with the lever 14 so that the oscillating movement of the lever 14 will expand and contract the bellows. This expanding and contracting movement of the bellows will draw air in through the pipe 38 and then force air out through said pipe, thus producing a breathing effect which will furnish sufficient blasts of air to effectively blow the thread ends *t'* away as fast as they are severed. The chamber 35 is herein shown as provided with a breather opening 47 so as to permit the bellows to be freely expanded or contracted without change of air pressure in the chamber.

While I have herein illustrated my invention as applied to a buttonhole sewing machine of the "Reece" type, yet I do not wish to be limited to this particular application of the invention as it is applicable to other types of sewing machines that are provided with means for holding the end of the thread while the initial stitches are being formed and then severing said end close to the work.

It will be understood, of course, that various constructional changes may be made in the parts of the invention without departing therefrom.

I claim:

1. In a sewing machine, the combination with stitch-forming mechanism, of work-clamping means, means to cause a relative movement between the stitch-forming mechanism and work-clamping means, of means to hold the end of the thread while the initial stitches are being formed and then to cut said end, and pneumatic means actuated by the means for giving such relative movement between the work-clamping means and stitch-forming mechanism to remove said severed end.

2. In a sewing machine, the combination with stitch-forming mechanism, of work-clamping means, means to cause a relative movement between the stitch-forming mechanism and work-clamping means, means to hold the end of a thread while the initial stitches are being formed and then to cut said thread, a bellows device, a pipe leading therefrom into position to deliver an air

blast onto the thread-holding and cutting means, and operating means for said bellows actuated by the means for giving the relative movement between the work-clamping means and stitch-forming mechanism.

3. In a sewing machine, the combination with a frame having a chamber therein, of stitch-forming mechanism, means to hold the end of the thread while the initial stitches 10 are being formed and then to cut said end, a bellows located in said chamber, a pipe leading from the bellows into position to deliver an air blast against said thread-holding and cutting means, and means to 15 actuate the bellows.

4. In a sewing machine, the combination with stitch-forming mechanism, of work-clamping means, means including an oscillating lever to cause a relative movement between said stitch-forming mechanism and 20 work-clamping means, a bellows device connected to and operated by said lever, and a pipe communicating with said bellows and leading into a position to deliver air blasts against said thread-holding and cutting 25 means.

In testimony whereof, I have signed my name to this specification.

JOHN KIEWICZ.
